UNITED STATES PATENT OFFICE.

DORRENCE W. LEPPERT, OF NORTH BERGEN, NEW JERSEY, ASSIGNOR TO S. BLICKMAN, INC., OF WEEHAWKEN, NEW JERSEY, A CORPORATION OF NEW JERSEY.

COLD-TOWEL HUMIDOR.

Application filed July 2, 1926. Serial No. 120,077.

This invention is an improvement in cold towel storage devices, and the invention relates more particularly to a device of the character specified of an ornamental nature, 5 and adapted for use in high class barber shops, beauty parlors and the like.

In the usual practice, cold towels used for face massage are prepared by dipping the towel in ice water and wringing out the 10 excess.

One of the primary objects of the present invention is the provision of a device for cooling the towels and retaining them in a cold condition and ready for use without 15 the necessity for dipping and wringing.

Another object is the provision of a device of the class described, having a normally closed cover, and means enabling lifting of the cover while leaving the hands of the 20 operator free.

Another object is the provision of a simple inexpensive ornamental device suitable for use in high class establishments.

With these and other objects in view the 25 invention consists in the construction and novel combination of parts fully described hereinafter, illustrated in the accompanying drawings, and pointed out in the claims appended hereto, it being understood that 30 various changes in the form, proportion, size and minor details of construction within the scope of the claims, may be resorted to without departing from the spirit of the invention.

35 In the drawings:

Fig. 1 is a vertical section of the improved device.

Fig. 2 is a plan view, with parts broken away.

40 In the present embodiment of the invention the improved device comprises a body, usually of cylindrical formation, and of jacketed construction, comprising an inner wall 1 and an outer wall 2, spaced apart 45 from each other to form an annular chamber 3 therebetween, within which is arranged heat insulating material of a suitable character. The body is supported by a pedestal which includes a cylindrical tubular body 50 portion 4 and an enlarged base portion 5.

A cover 6 is provided for closing the open top of the body, and the said cover is double walled or jacketed, in the same manner as the body. The cover is hinged at 7 to the 55 body in any suitable manner, and it will be

noticed referring to Fig. 1, that the top of the body is mitred or beveled as shown. The pivot of the hinge connection between body and cover is offset outwardly beyond the exterior of the body as shown to provide 60 for a wide opening of the cover.

Mechanism is provided for enabling the cover to be opened by the foot of the operator, leaving the hands free to remove a towel, and to wring out the excess water 65 if necessary. This mechanism includes a treadle or lever 8, which passes through a vertical slot or opening in the body of the pedestal, and is pivoted as indicated at 9 within the said body. The forward end of 70 the lever is provided with a foot plate 10 for convenience in swinging the same, and the rear end is provided with laterally diverging arms 11, which are connected by links 12 with bracket plates 13 on the cover. 75

The arrangement of the lever and the links is such that when the forward end of the lever is depressed, the arms 11 are lifted, lifting the links 12, and the cover thus to enable access to the interior thereof, while 80 leaving the hands of the operator free.

Means is provided for cushioning the closing movement of the cover. The said means is a dash pot, comprising a cylinder 14, in which is a piston connected by a rod 15 with 85 the treadle or lever 8. The dash pot is arranged in front of the pedestal, and as is usual in such constructions a by-pass of variable capacity is provided for enabling adjustment of the cushioning effect. In the 90 present instance, the chamber within the body, which is designed to hold ice, upon which the towels may be stored, is provided with a central drain opening, normally closed by plug 16. The plug is a valve, 95 operated to open and closed position by means of a valve stem 17.

In use, ice in suitable quantity is placed in the insulated chamber in the body. The towels may be placed upon the ice, or a suitable holder may be provided for the towels. When a towel is desired, the lever is operated to raise the cover, giving access to the towel. As soon as the lever is released, the cover descends by gravity into closed 105 position, the movement thereof being cushioned by the dash pot.

What is claimed as new is:

1. A cold towel storage device, comprising a body and a pedestal for supporting 110

the body in elevated position, said body having an insulated ice and towel storage chamber, and an insulated cover for the chamber hinged to the body, a lever extending transversely through the pedestal and pivoted thereto, links connecting the rear end of the lever with opposite sides of the cover for lifting the same when the front end of the lever is depressed, the cover arranged to close by gravity, and means to cushion the closing means of the cover arranged between the front end of the lever and that part of the body which extends beyond the pedestal, and within the circumference of the body.

15 2. A cold towel storage device, comprising a body and a pedestal for supporting the body in elevated position, said body having an insulated ice and towel storage chamber

20 hinged to the body, a lever extending transversely through the pedestal and pivoted thereto, links connecting the rear end of the lever with opposite sides of the cover for lifting the same when the front end of the lever is depressed, the cover arranged to 25 close by gravity, a cylinder supported by the body between the bottom of the same and the lever and within the circumference of the body, and a piston in the cylinder connected with the lever for cushioning the 30 closing movement of the cover.

Signed at Weehawken in the county of Hudson and State of New Jersey this 29th day of June, A. D. 1926.

DORRENCE W. LEPPERT.
